(57) **CLAIM**

The ornamental design for a window shade, as shown and described.

DESCRIPTION

FIG. 1 is a front view of a window shade according to the present invention in a closed position.

FIG. 2 is a perspective view of a window shade according to the present invention in a closed position.

FIG. 3 is a side view of a window shade according to the present invention in an open position.

FIG. 4 is a bottom view of the window shade of FIG. 2.

FIG. 5 is a front view of a first embodiment of a window shade according to the present invention in an open position.

FIG. 6 is a front view of a second embodiment of a window shade according to the present invention in an open position.

FIG. 7 is a front view of a third embodiment of a window shade according to the present invention in an open position.

FIG. 8 is a front view of a fourth embodiment of a window shade according to the present invention in an open position; and,

FIG. 9 is a perspective view of the embodiment of the window shade of FIG. 6.

The broken lines showing of a window, back portion of the shade, and on the front portion of the shade in FIGS. 1–9 are for illustrative purposes only and form no part of the claimed design.
